UNITED STATES PATENT OFFICE.

FRED S. ATKINSON, OF BROOKLINE, MASSACHUSETTS.

MECHANICALLY-SIMULATED BASEBALL GAME.

Application filed April 27, 1927. Serial No. 187,034.

This invention relates to a game apparatus by which a game similar to a baseball game can be played. The device is of that known type which comprises a visible representation of a baseball field, a ball which is adapted to be projected or actuated by the application of force and means operative when the ball is actuated to indicate the value of the play.

10 In the present invention the ball is suspended and when it is projected either by being struck with a bat or by the application of force in any other way the signal-actuating device is stepped forward one step. Each time that the signal-actuating device is thus stepped forward it will exhibit a signal which will indicate the value of the play. In the present invention while the signal-actuating device is rendered operative by the ball being projected yet its operation does not depend upon the force with which the ball is projected as projecting the ball with a relatively gentle force will bring the same result as if the ball were projected 20 with a great force. As the device is operated the signals are displayed in a predetermined sequence which, however, is unknown to the person playing the game.

The features wherein my present invention reside will be more fully hereinafter set forth and then pointed out in the appended claims.

Referring now to the drawings wherein I have illustrated a selected embodiment of my invention, Fig. 1 is a front view of a game apparatus embodying my invention; Fig. 2 is a section on the line 2—2, Fig. 1;

Fig. 3 is a diagrammatic view showing the electrical wiring for the system;

40 Fig. 4 is a fragmentary view of the actuator by which the signals are controlled;

Fig. 5 is a view showing the device for rendering the apparatus operative upon deposit of a coin;

45 Fig. 6 is a side view of Fig. 5.

Fig. 7 is a fragmentary view of the signal-circuit closing device.

The apparatus is herein shown as placed within a suitable cabinet 1 which has depicted on its front face a representation of a baseball diamond as shown at 2. 3 indicates a suspended ball which is adapted to be projected by the application of force thereto. This projection of the ball may be 50 accomplished either by hitting the ball with

the bat or by throwing the ball or by applying force thereto in any desirable way. In the present invention said ball is supported from a hollow arm 4 that extends laterally from the cabinet 1 in any desired 60 position relative to the representation of the diamond 2. Said arm is provided with the right angular portion 5. The ball 3 is supported by a cord 6 which extends upwardly through the portion 5 of the arm 4 and then 65 into the horizontal portion thereof, said cord being connected to a plunger member 7 which is slidably mounted in the arm and is backed by a spring 8. This spring is shown as situated within the arm 4 between the 70 plunger 7 and a fixed collar 9 through which the flexible cord 6 passes. The arm 4 is swivelled in the cabinet 1 so that it can turn about the axis of the horizontal portion thereof.

When the ball 3 is struck a blow with the baseball bat or is thrown by hand or otherwise projected the momentum of the ball will cause the arm 4 to rotate as will be obvious and since the portion 5 of the arm extends radially to the circular path of the ball the centrifugal force of the ball will compress the spring 8 somewhat.

Associated with the baseball diamond 2 are a plurality of signals for indicating the 85 value of the hit and means are provided whereby the compression of the spring 8 due to the centrifugal force on the ball 3 when it is projected will set the signal mechanism in operation.

Any desirable number of signals may be employed without departing from the invention. As herein shown the diamond is provided with a signal 10 at first base, a signal 11 at second base, a signal 12 at third base, a signal 14 at the home plate, a signal 15 in the pitcher's box and a signal 16 in the catcher's position. As stated above, however, additional signals may be used if it is desired. The different signals may indicate 95 any desired values for the hit. Merely for illustrative purposes the signal 10 is shown as indicating one base hit, the signal 11 a home run, the signal 12 three base hit, the signal 14 a strike out, the signal 15 a put-out, and signal 16 a foul.

These signals may have any desired construction without departing from the invention. They may be simply electric lights which will be illuminated or they may be in 110

the form of annunciators or any other familiar signal. Merely for illustrative purposes and in order not to complicate the drawings, I have shown the signals as in the form of electric lights which are mounted on a panel 17 within the cabinet 1 and are visible through sight openings 18 formed in the front of the cabinet. The operation of these signals is controlled by a commutator or signal-controlling member which is intermittently actuated; it being stepped forward one step each time that the ball 3 is struck. The signal-actuating device herein illustrated comprises a signal circuit having a plurality of stationary contacts therein connected to the various signal devices and a contact having an intermittent uni-directional movement which is stepped forward one step each time the ball 3 is struck and which in its forward movement engages the stationary contacts successively. These stationary contacts are indicated at 19 and they are mounted on a suitable supporting plate 20 of insulating material. The movable contact is indicated at 21 and it is mounted on a shaft 22 journaled in the supporting block 20 and also in a supporting member 42 which stands parallel to the block 20. The contacting arm 21 carries at its outer end a brush or contact member 23 adapted to engage the contacts 19 successively as the shaft 22 rotates.

Means are provided for moving the shaft forward with an intermittent motion, each forward step being sufficient to carry the brush 23 from one contact 19 to the next. The means for stepping the brush forward intermittently comprises a ratchet wheel 24 fast on the shaft 22, there being as many teeth on the ratchet as there are contacts 19, and a pawl 25 by which the ratchet is intermittently stepped forward. This pawl is a spring-pressed pawl pivotally mounted on the end of a lever 26 which is pivoted at 27 to the supporting member 20. The lever is actuated by a magnet 28; the armature 29 of which is carried on the end of the lever 26. The lever 26 is acted on by a spring 30 which tends normally to hold it in the position shown in Fig. 4 and which furnishes the motive power for giving the ratchet its forward movement, the magnet 28 serving as means for retracting the pawl.

When the magnet is energized it will attract its armature 29 thus rocking the lever 26 into the dotted line position Fig. 4 and as soon as the magnet 28 is de-energized the spring 30 will return the lever to the full line position Fig. 4 and thus step the ratchet wheel forward one step.

Means are provided whereby the magnet 28 will be energized whenever the ball 3 is projected either by being struck with a bat or by application of force in any other way. For this purpose the circuit of the magnet

has therein two normally open contacts which are closed whenever the spring 8 is compressed due to the ball 3 being hit. These contacts are indicated at 32 and 33 respectively. The contact 33 is in the nature of a resilient arm mounted on a support 92 of insulating material. The contact 32 is in the form of a pin or projection carried by a rocking member 34 that is pivotally mounted at 91.

This member 34 contacts with a spring arm 93 mounted on a support 94 of insulating material, said arms 93 and 33 being connected in the circuit of the magnet 28. The member 34 is provided with two flat faces 90, 95, 96 having an angular relation to each other and which are engaged by the spring arm 93; the latter serving to maintain the swinging member 34 yieldingly in either of the two positions. Said member 34 is a forked member, it having the two arms 97, 98. The plunger 7 is provided with an extension 99 which carries at its end a disk 89 that is adapted to co-operate with the arms 97, 98 for opening and closing the contacts 32, 33. Normally the contacts are open as shown in full lines Fig. 2 and the member 34 is in the position with the spring arm 93 bearing against the flat face 96. The edge of the disk 89 is located between the arms 97, 98.

When the ball is struck or projected and the arm 4 begins to rotate the centrifugal force of the ball will compress the spring 8 and will move the head or disk 89 to the left Fig. 2 thereby causing it to engage the arm 98 of the member 34 thereby turning the member 34. When the member has been turned sufficiently so that the point 88 between the flat surfaces 95, 96 has been carried past the center line then the resiliency of the spring arm 93 which has been flexed backwardly by the turning movement of the member 34 will act on the point 88 to give the member 34 a quick snap action into the dotted line position. This will close the contacts 32, 33 thus closing the circuit of the magnet 28. When the member 34 is in this position the arm 98 has been carried out of the path of movement of the disk 89 so that the latter is free to move to any extent dependent on the centrifugal force acting on the ball 3.

When the force with which the ball was projected has been expended then the spring 8 will expand thus forcing the disk 89 to the right during which movement the disk will engage the arm 97 and will swing the member 34 back into its full line position thus separating the contacts 32, 33. Each time the ball is hit, therefore, the magnet 28 will be energized momentarily thereby retracting the pawl 25 and as soon as the force with which the ball was projected has been expended the circuit of the magnet will be

opened and the magnet will be de-energized so that the spring 30 will give the ratchet its forward step. Each forward step of the ratchet and of the contact arm 21 with its shoe 23 will light one of the signal lights thereby indicating the value of the play.

The contacts 32, 33 comprise a switch which operates with a snap action, the advantage of which is that whenever the ball 10 is projected the switch will be positively closed and then will remain closed until the force with which the ball was projected has been expended when it will be quickly opened. The actual separating and closing 15 of the contacts is accomplished by the spring arm 93, the disk 89 and spring 30 serving to place the spring arm 93 under compression to permit it to function in giving the switch its snap action.

20 The contacts 19 extend through the supporting plate 20 and are connected by suitable wires 50 with the various signal lamps. This wiring may be so arranged that the signal lamps will be illuminated in any desired sequence as the contact arm 21 is rotated.

My improved apparatus is also so constructed that in order to operate it it is necessary to drop a coin into a coin chute 30 and the device is also so constructed that after the apparatus has been rendered operative by the dropping of a coin in the coin chute it will remain in operative condition until the "out" signals have been operated for three times, thus indicating that three men have been put out and that the side has been retired, at which time the signal device will become inoperative and will remain inoperative until another coin has 40 been deposited in the coin chute.

To accomplish this I provide a coin-controlled make-and-break device in the circuit of the magnet 28 and also provide means for opening this circuit when the necessary 45 three "outs" have been recorded by the signals.

While various devices for accomplishing this may be employed that which is herein shown is deemed to be a practical one.

50 In the wiring diagram shown in Fig. 3 the magnet 28 is illustrated as being energized from a battery 35, it being connected to the battery through a circuit 36 which has therein the contacts 31, 32 and also has therein the make-and-break device. This make-and-break device is shown as a rotatable contact member 37 which is fast on the shaft 22 and a stationary contact member 38. The rotary contact member 37 is provided with a stepped surface having a plurality of cam faces 39.

While the game is being played the contact arm 38 rests on one of the cam faces 39 thus completing the circuit 36 at this point 65 but after three "outs" have been recorded

the contact 38 is separated or raised from the contact member 37 as shown in Fig. 3 thus opening the circuit at this point.

The contact member 38 is held in its inoperative position by means of a latch 40 pivoted at 41 to the plate or supporting member 42 which stands parallel to the supporting block 20. This latch is adapted to be released upon deposit of a coin in the coin chute 43 formed in the casing. For this purpose I employ a latch-releasing magnet 44, the armature 45 of which is connected to or forms part of the latch 40 so that when the magnet is energized and the armature raised the latch will be swung about its pivot 41 and thus withdrawn from operative engagement with the contact member 38. This latch-releasing magnet 44 is connected in a circuit 46 which is tapped off from the circuit 36 and which has therein two contacts 47 adapted to be closed by a movable contact 48. This movable contact 48 is pivotally mounted at 49 and normally will be separated from the contacts 47 as shown in Fig. 2. The contact 48 is provided with an extension 60 situated beyond the pivot 49 and located beneath the lower end of the coin chute 43.

When a coin 51 is deposited in the chute it will upon emerging therefrom drop onto the extension 60 and the weight of the coin will be sufficient to overbalance the contact and raise the latter against the contacts 47 thus closing the circuit 46 of the latch-releasing magnet 44 with the result that the latch 40 is released from its engagement with the contact 38 and the latter closes onto the contact 39. The closing of the contacts 38, 39 closes the circuit 36 of the signal-actuating magnet 28 at this point and puts the machine in condition to be operated by hitting the ball 3 with the bat.

As the shaft 22 is stepped forward by the repeated actuations of the magnet 28 the contact arm 30 will ride up the incline 39 and by the time the high portion 52 of the cam surface is under the contact 38 it will have been raised above the shoulder 53 of the latch 40. As the contact 38 is gradually raised by the cam surface 39 it engages the incline face 54 of the latch and crowds the latch backwardly.

As stated above by the time the high point 52 of the cam is in engagement with the contact 38 the latter has been elevated above the shoulder 53 and the weight of the latch 40 causes it to swing into position with the shoulder 54 underneath the contact 38. When the member 37 has finally been advanced to a point where the high portion 52 passes out from under the contact 38 the latter will move downwardly under its own resiliency until it is arrested by the shoulder 53 of the latch 40, such shoulder holding the arm separated from the

wheel 38 and thus opening the circuit at this point. This renders the game apparatus inoperative until another coin has been deposited in the chute 43 thereby to close the circuit at the point 37, 38.

The contact member 37 may have one or more cam surfaces 39. In other words, the arrangement may be so that each time a coin is deposited and the game apparatus is 10 rendered operative the shaft 22 may make a complete rotation before it is rendered inoperative or the construction may be such that the signal device will be rendered inoperative after the shaft has made a partial 15 rotation.

In the construction shown the arrangement is such that after the shaft has made one-third of a rotation the signal device will be rendered inoperative for which purpose 20 there are three cam surfaces 39 on the member 37. With this arrangement the annular row of signal contacts 19 will be divided into three groups or sections, there being in each group three contacts leading to the 25 "out" signal, the next to the last contact of each group being one of these. The last contact of each group which is indicated at 19^a is a blank, that is, it is not connected to any signal.

30 The operation of the device will be readily understood from the above.

The apparatus normally is in the position shown in the drawings, the circuit 36 open at 31, 32, and also open at 37, 38, and the 35 contact 38 being held in inoperative position by the latch 40. The circuit 46 of the latch-releasing magnet 44 is also normally open as shown in Fig. 3.

To use the device the operator first 40 deposits a coin 51 in the coin chute 43 which will close the circuit 46, cause the latch-releasing magnet 34 to be energized thereby releasing the latch 40 and allowing the contact 38 to close onto the contact 39. The 45 game is then in condition for operation and the operator or player will apply force to the ball 3 to project the latter either by striking the ball with a bat or throwing the ball by hand or in any other desired way. 50 Since the ball is connected to the cord 6 the force which is thus applied to the ball will cause the arm 4 to rotate and the centrifugal force to which the ball is subjected will compress the spring 8 and allow the contacts 31, 32 to close thus energizing the signal-actuating magnet 28 which will step the shaft 22 and the contact 21 forward one step. It 55 may be remarked at this point that when the machine is at rest normally the contact 23 is on one of the blank contacts 19^a so that no signal is exhibited.

In the construction shown there are thirty 60 contacts 19 and these are divided into three groups of ten each indicated generally by *a*, *b* and *c*, the contacts of each group having

three that connect to signals indicating "out", the next to the last contact of each group being one of these and the last contact of each group being a blank 19^a. Each time that the ball 3 is hit the circuit 36 is 70 closed on the contacts 31, 32 and the shaft 22 stepped forward one step thus carrying the brush 23 from one contact to the next. As the brush engages each contact the circuit is closed through the corresponding signal 75 80 thus illuminating it and indicating the value of the hit. When the ball has been struck or projected ten times the shaft 22 will have been turned through a third of a revolution and the member 37 will have been advanced 85 to a point wherein one of the high parts 52 of the member 37 has been carried out from under the contact 38. As the contact 38 is raised by the cam 39 it wipes by the latch 40 and when the high part of the cam passes 90 out from under the contact 38 the latter drops down against the latch 40 which holds it out of contact with the contacts 37 and thus opens the circuit 36 at this point. This renders the device inoperative until 95 another coin has been dropped in the chute 43.

I claim:

1. In a baseball game apparatus, the combination with a plurality of signals indicative of different stages of the game, of a uni-directional intermittently-operating signal-actuating device, the successive forward steps of which operate to exhibit the signals successively, a suspended ball adapted 100 to be projected, and means rendered operative each time said ball is projected to step the signal-actuating device forward one step.

2. In a baseball game apparatus, the combination with a plurality of signals indicative of different stages of the game, of a uni-directional intermittently-operating signal-actuating device by which the signals are exhibited successively, a suspended ball 110 adapted to be projected by the application of force, means rendered operative each time said ball is projected to step the signal-actuating device forward one step, and means to render the signal-actuating device inoperative after it has been stepped forward a predetermined number of steps.

3. In a game apparatus, the combination with a plurality of signals indicative of different stages of the game, of an electrically-operated uni-directional signal-actuating means by which the signals are exhibited successively, said means including a normally-open circuit, a suspended ball adapted to be projected, and means for momentarily closing the circuit of the signal-actuating means thereby rendering the same operative each time the ball is projected.

4. In a game apparatus, the combination with a plurality of signals indicative of 130

different stages of the game, of an electrically-operated signal-actuating means by which the signals are exhibited successively, said means including a normally-open circuit, a suspended ball adapted to be hit with a bat, means for momentarily closing the circuit of the signal-actuating member thereby rendering the same operative each time the ball is projected, and other means for opening said circuit when said circuit has been momentarily closed a predetermined number of times.

5. In a game apparatus, the combination with a plurality of signals indicative of different stages of the game, of an electrically-operated intermittently-operating signal-actuating member having a uni-directional movement, a normally open circuit, a suspended ball adapted to be projected, and means to close momentarily said circuit whenever the ball is so projected and means to step the signal-actuating mechanism forward one step each time the circuit is closed.

6. In a game apparatus, the combination with a plurality of signals indicative of different stages of the game, of an electrically-operated intermittently-operating signal-actuating member having a normally open circuit, a suspended ball adapted to be projected, means to close momentarily said circuit whenever the ball is so projected thereby to step the signal-actuating mechanism forward one step, and means to render the signal-actuating mechanism inoperative when it has been stepped forward a predetermined number of times.

7. In a game apparatus, the combination with a plurality of signals indicative of different stages of the game, of signal circuits therefor, each having a contact therein, a movable contact arm having a uni-directional movement and by which the contacts are closed successively, a suspended ball adapted to be projected, and means operative each time the ball is projected to step the contact arm forward one step.

8. In a game apparatus, the combination with a plurality of signals indicative of different stages of the game, of signal circuits therefor, each having a contact therein, a movable contact arm by which the contacts are closed successively, a suspended ball adapted to be projected, means operative each time the ball is projected to step the contact arm forward one step, and means to render the last-named means inoperative after the ball has been projected a predetermined number of times.

9. In a game apparatus, the combination with a plurality of signals indicative of different stages of the game, signal circuits for operating the signals each having a contact therein, a contact arm having a uni-directional movement and adapted to engage the contacts successively, a magnet for

intermittently actuating said contact arm, a normally-open circuit for the magnet, a ball adapted to be projected by the application of force, and means to close said circuit each time the ball is projected.

10. In a baseball game apparatus, the combination with a plurality of signals indicative of different stages of the game, an electrically-actuated signal-actuating mechanism including a circuit having normally open contacts therein, a tubular ball-supporting member having a horizontal portion and a vertical portion, means supporting said member so that it may turn about the axis of the horizontal portion, a ball suspended from the vertical portion of said member, whereby when the ball is given an impulse the tubular member is rotated about the horizontal portion as an axis, and circuit-closing means controlled by the centrifugal force of the ball.

11. In a game apparatus, the combination with a casing, of a tubular ball-supporting arm having a horizontal portion rotatably mounted in said casing and having a vertical portion, a plurality of signals indicative of different stages of the game, signal-actuating means including a circuit having contacts therein, a spring for normally holding the contacts open, a ball suspended from said arm and adapted when given an impulse to cause the arm to rotate, said spring being opposed by the centrifugal force on the ball when the arm rotates, whereby the impulse given to the ball permits the contacts to close and the signal-actuating member to be operated.

12. In a game apparatus, the combination with a plurality of signals indicative of different stages of the game, of an intermittently-operating signal-actuating device by which the signals are exhibited successively, a ball adapted to be projected by the application of force, and means rendered operative each time the ball is projected to step the signal-actuating device forward one step whether the ball is projected with a relatively small force or a relatively great force.

13. In a baseball game apparatus, the combination with a plurality of signals indicative of different stages of the game, of a uni-directional intermittently-operating signal-actuating device by which the signals are exhibited successively and the successive forward steps of which are of the same amplitude, a captive ball adapted to be projected, and means rendered operative each time the ball is projected to step the signal actuating device forward one step.

14. In a baseball game apparatus, the combination with a plurality of signals indicative of different stages of the game, of a uni-directional intermittently-operating signal-actuating device by which the signals

are exhibited successively and the successive forward steps of which are of the same amplitude, a captive ball adapted to be projected, means rendered operative each time the ball is projected to step the signal-actuating device forward one step, and means to render the signal-actuating device inoperative after it has been stepped forward a predetermined number of steps.

10 15. In a game apparatus, the combination with a plurality of signals indicative of different stages of the game, of an electrically-operated intermittently-operating signal-ac-

tuating member, said member having a unidirectional movement and each forward step thereof being of the same amplitude, said signals being operated successively and in a predetermined sequence by the intermittent operation of said member, a captive ball adapted to be projected, and means operative whenever the ball is projected to advance the signal-actuating member forward one step.

In testimony whereof, I have signed my name to this specification.

FRED S. ATKINSON.
